United States Patent

Des. 237,778
Patented Nov. 25, 1975

237,778

BOTTLE

Rene Lorgues, 5 Quai d'Anjou, Paris 4, France

Filed May 13, 1974, Ser. No. 469,338

Term of patent 14 years

Int. Cl. D9—01

U.S. Cl. D9—159

FIG. 1 is a top plan view of a bottle showing my new design;

FIG. 2 is an elevational view of the bottle taken along the line 2—2 of FIG. 1;

FIG. 3 is a bottom plan view; and

FIG. 4 is a sectional view taken on the line 4—4 of FIG. 3.

The view opposite that shown in FIG. 2 is identical in appearance.

I claim:

The ornamental design for a bottle, as shown and described.
